UNITED STATES PATENT OFFICE

146,548

DESIGN FOR A COMBINED RADIO, CLOCK,
AND BED LAMPMichael F. Valinski and Ernest W. Leyva,
San Diego, Calif.

Application February 15, 1946, Serial No. 126,596

Term of patent 3½ years

(Cl. D56—4)

To all whom it may concern:

Be it known that we, Michael F. Valinski and Ernest W. Leyva, citizens of the United States, residing at San Diego, in the county of San Diego and State of California, have invented a new, original, and ornamental Design for a Combined Radio, Clock, and Bed Lamp, of which the following is a specification, reference being had to the accompanying drawing, forming a part thereof.

Figure 1 is an end elevational view of a combined radio, clock, and bed lamp, showing my new design;

Figure 2 is a rear elevational view; and

Figure 3 is a bottom plan view thereof.

We claim:

The ornamental design for a combined radio, clock, and bed lamp, as shown.

MICHAEL F. VALINSKI.
ERNEST W. LEYVA.
